Frank Liebenow; Justin P. Miller(57) **CLAIM**

The ornamental design for a four-way neck exercising harness, as shown and described.

DESCRIPTION

FIG. 1 is a perspective view of a four-way neck exercising harness showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof showing how the four-way neck exercising harness is used.
Portions of the four-way neck exercising harness shown in broken lines and the head in FIG. 8 form no part of the claimed design.**1 Claim, 7 Drawing Sheets**FIG. 1
